Primary Examiner — Wan Laymon(74) *Attorney, Agent, or Firm* — Boyle Fredrickson, S.C.**CLAIM**

The ornamental design for a tool base for dental endodontic tips, as shown and described.

DESCRIPTION

FIG. 1 is a perspective view of a tool base for dental endodontic tips incorporating my new design;

FIG. 2 is a front elevation view thereof;

FIG. 3 is a top plan view thereof; and,

FIG. 4 is a bottom plan view thereof.

The dashed lines in FIGS. 1–4 are for illustrative purposes only and form no part of the claimed invention.
